YARN HOLDER FOR BOBBIN TRANSFER MAGAZINES

George W. Parkin, Esmond, R. I.

Application November 24, 1943, Serial No. 511,568

11 Claims. (Cl. 139—247)

This invention relates to holding the weft yarn which extends from a bobbin transfer magazine of a loom.

Various devices have been used for holding the yarn which extends from the bobbin of the transfer magazine. Those which have become more or less standard equipment in weave rooms are located a substantial distance from the magazine so that the angles which are formed between the bobbins which gravitate downwardly in the magazine and the point at which the ends of the yarn are held will not be too abrupt. This distance requires a substantial length of yarn for this lead and thus for each bobbin a considerable length of yarn is wasted. This length of waste when multiplied by the large number of bobbins which are used becomes a substantial amount.

One of the objects of this invention is to provide an arrangement so that the gripped end of the yarn will travel with the bobbin in its downward gravitation so that but a short extent of yarn from the bobbin to the holder will be necessary.

Another object of this invention is to provide an arrangement so that the gripped end of the yarn will be discharged after the holding thereof has performed its useful function.

Another object of the invention is to so hold the yarn that a tension will be provided upon the end at all times that the yarn may be nicely controlled.

Another object of this invention is to provide a device which will be light in weight and one which may be easily and quickly assembled upon all looms which are now in operation.

Another object of this invention is to provide an arrangement so that the cut end of the yarn will be prevented from dropping into the lay to serve as an obstruction to the moving shuttle.

With these and other objects in view, the invention consists of certain novel features of construction, as will be more fully described and particularly pointed out in the appended claims.

In the accompanying drawing:

Fig. 1 is an elevation looking at the bobbin magazine and illustrating the lay in section with the shuttle in position in a box beneath the magazine, also showing my yarn holder in its relative position;

Fig. 2 is an end view of the structure shown in Fig. 1 with the lay omitted;

Fig. 3 is a fragmental sectional view of a part of the magazine but showing my holding device in top plan;

Fig. 4 is an enlarged fragmental sectional view

of a part of one of the drums and the clamping device which is associated with the belt after the clamp has moved to release its grip upon the yarn ends;

5 Fig. 5 is a sectional view through one of the drums showing a small bearing mounting;

Fig. 6 is a sectional view on line 6—6 of Fig. 2.

In proceeding with this invention I provide an arrangement which may be placed closely to the 10 bobbin magazine, for example within four to six inches if desired. The arrangement is such that the clamps for the yarn ends will travel about an orbit so that as the bobbins gravitate downwardly in the magazine the clamped ends will move whereby the short lead to the clamp need not be extended. After the bobbin is transferred into the shuttle as the clamp travels about the end of the orbit its position becomes such that the 15 yarn end will be released and removed from the clamp permitting the cut ends to be easily gathered up. A plate which assists in stripping the yarn ends from the clamping device also so controls the yarn ends that they cannot get into part of the loom where jamming may occur.

25 With reference to the drawing, 10 designates generally a bobbin magazine with a plurality of bobbin packages 11 therein. This magazine usually consists of end walls 12 and 13, the latter of which is provided with slots 14 and 15 through which the ends of yarn may extend. The magazine which is here illustrated consists of four lines for four stacks of bobbins with the yarn ends of parallel rows extending through the slots 14 and 15 as shown at 16. The lay designated generally 30 17 is shown fragmentally in Fig. 1 and is cut away to expose a shuttle 18 into which one of the packages now designated 19 is illustrated in dotted lines. The end 20 of this bobbin package is shown as extending to the holding device.

35 40 The bobbins are supplied to the magazine from time to time and each end such as 16 from these bobbins is lead outwardly through the slots 14 or 15 to a holding device.

The holding device which I have provided is 45 mounted on the end plate 13 and consists of a rod or bar 21, see Figs. 1, 2, and 6, which is firmly mounted by means of a bolt 22 so that it will extend outwardly from the plate 13. From the end of this bar, arms 23 and 24 are mounted by 50 means of the set screw 25 and binding bolt 26 so that the arm 23 extends upwardly slightly at an angle to the horizontal while the arm 24 extends vertically upwardly from this arm 23. This bracket-like formation serves to mount a pair of drums. The upper drum 27 is mounted by

means of the pin 28 on a ball bearing 29. The reduced portion 30 of this pin extending through the arm 24 and is held in position by a nut 31, binding upon the washer 32. The drum 33 is mounted upon a similar pin designated 28' having a ball bearing and a reduced portion 30' which is somewhat longer than the portion 30 in order that it may extend through arms 23 and 24 and bind them in such position as they may be desired to assume.

Both drums 27 and 33 are grooved as at 34 and a belt 35 extends about these drums and is prevented from lateral movement by the flanges on either side of the groove 34. Clamps designated generally 36 and shown somewhat larger in Fig. 4 have a base portion 37 which is riveted as at 38 to the belt 35. The base 37 is provided with a hinge ear 39 providing a hinge pivot 40 for the clamping arm 41 which has a handle portion 42 and which is urged into clamping position against the straight portion of the belt by a spring 43 acting between the handle 42 and the base 37. When these clamps are along the straight run of the belt they are forced into engagement with this straight run of belt by the springs 43. However, as the clamps move about the drum as shown in Fig. 4 they will move away from the belt so as to permit the group of ends such as 16 which may be held between the arms 41 and the belt to be moved from position.

The ends 16 which extend through the slots 14 and 15 are carried over to the clamp, there being perhaps eight to twelve ends positioned in a single clamping unit. This is easily accomplished by grouping these ends together and pressing on the handle 42 to move the arm 41 away from the belt and then positioning the group of threads therein and releasing the handle 42 to permit the spring to press the yarns tightly against belt and hold them in position. As the bobbins from the lower end of the magazine are positioned in the shuttle the entire group of bobbins above moves downwardly. As this downward movement occurs there is sufficient pull upon the clamp to move the belt and the clamp downwardly. The ball bearings enable the belt to have this free movement. This grip upon the yarn from each bobbin is maintained until that bobbin is inserted in the shuttle and the shuttle travels across the loom for the first pick, after which the cutter operates to cut off this end close to the selvedge. As succeeding bobbins pull the belt downwardly the clamp arrives at a point to pass about the drum 33 as shown in Fig. 4 and this clamp moves away from the belt 35 so as to release the yarn ends 16 which have been clamped thereby.

In order to strip the yarn ends from the belt and to prevent these yarn ends from moving into parts of the loom where they are not desired I have provided a plate 45 which is slotted as at 46 to receive the arm 23 therethrough and which is slotted as at 47 to receive the drum and the clamps therethrough as shown in Fig. 3. However, the yarn ends such as 20 which extend across this plate will not pass downwardly after they engage the plate but rather will be stripped at the plate while the belt and the clamp move onwardly leaving these yarn ends on the plate (see the group designated 16 in Fig. 4). By this arrangement these cut yarn ends may be nicely controlled and gathered up at intervals so that this waste will not get into moving parts of the loom.

The arrangements which I have provided by the gripped ends of the yarn moving downwardly

with the bobbin as they gravitate in the magazine make it possible to locate this yarn end holder close to the magazine and thus no long extent such as a yard or more is necessary, my device being operable at a distance of four inches to six inches with a consequent saving of the difference in length between the distance at which my holder may be mounted and that at which other holders are mounted in order to have a sufficiently long lead so that convenient operation without too great a stressing on the yarn may be prevented.

I claim:

1. In a weft replenishing loom, a bobbin magazine having a reserve supply of bobbins movable by gravity, said magazine having a slot through which the weft ends extend, a weft end holder adjacent the magazine provided with means to engage the weft ends and hold the same under tension, said engaging means being movable by the pull of the weft ends thereon as the bobbins from which the ends extend move in said magazine.

2. In a weft replenishing loom, a bobbin magazine having a reserve supply of bobbins movable by gravity, said magazine having a slot through which the weft ends extend, a weft end holder mechanism adjacent the magazine provided with a plurality of means to engage a group of the weft ends and hold the same under tension, said engaging means being movable by the pull of the weft ends thereon as the bobbins from which the ends extend move in said magazine.

3. In a weft replenishing loom, a bobbin magazine having a reserve supply of bobbins movable by gravity, said magazine having a slot through which the weft ends extend, a weft end holder mechanism adjacent the magazine provided with a plurality of means to engage a group of the weft ends and hold the same under tension, means to mount said engaging and holding means for movement in a closed orbit, said engaging means being movable by the pull of the weft ends thereon as the bobbins from which the ends extend gravitate downwardly in said magazine.

4. In a weft replenishing loom, a bobbin magazine having a reserve supply of bobbins movable by gravity, said magazine having a slot through which the weft ends extend, a weft end holder adjacent the magazine provided with means to engage the weft ends and hold the same under tension, said engaging means being movable by the pull of the weft ends thereon as the bobbins from which the ends extend move in said magazine, and means to cause the engaged weft ends to become released and discharged from the holder at a predetermined point in their travel.

5. In a weft replenishing loom, a bobbin magazine having a reserve supply of bobbins movable by gravity, said magazine having a slot through which the weft ends extend, a weft end holder mechanism adjacent the magazine provided with a plurality of means to engage a group of the weft ends and hold the same under tension, means to mount said engaging and holding means for movement in a closed orbit, said engaging means being movable by the pull of the weft ends thereon as the bobbins from which the ends extend gravitate downwardly in said magazine, and means to cause the engaged weft ends to become released and discharged from the holder at a predetermined point in their travel.

6. A thread holder for a weft replenishing loom having a reserve supply of bobbins from which extend weft ends, comprising a pair of drums each freely rotatably mounted in spaced relation

and rotatable in a plane substantially at right angles to the axes of the bobbins, a flexible belt on said drums and a plurality of clamps on said belt in spaced relation for holding the weft ends of the bobbins.

7. A thread holder for a weft replenishing loom having a reserve supply of bobbins movable by gravity and from which extend weft ends, comprising a pair of drums each freely rotatably mounted in spaced relation and rotatable in a plane substantially at right angles to the axes of the bobbins, a flexible belt on said drums and a plurality of clamps on said belt in spaced relation for holding the weft ends of the bobbins, said drums being sufficiently freely rotatable for the weft ends to rotate the drums as the bobbins gravitate downwardly in the magazine.

8. A thread holder for a weft replenishing loom having a reserve supply of bobbins from which extend weft ends, comprising a pair of drums each freely rotatably mounted in spaced relation and rotatable in a plane substantially at right angles to the axes of the bobbins, a flexible belt on said drums and a plurality of clamps on said belt in spaced relation for clamping the weft ends of the bobbins against the belt.

9. A thread holder for a weft replenishing loom having a reserve supply of bobbins from which extend weft ends, comprising a pair of drums each freely rotatably mounted in spaced relation and rotatable in a plane substantially at right angles to the axes of the bobbins, a flexible belt on said drums and a plurality of clamps on said belt in spaced relation for clamping the weft ends of the bobbins against the belt, each clamp being

so mounted as to move away from the belt as it travels about the drum to release its clamping engagement with the weft ends.

10. A thread holder for a weft replenishing loom having a reserve supply of bobbins from which extend weft ends, comprising a pair of drums each freely rotatably mounted in spaced relation and rotatable in a plane substantially at right angles to the axes of the bobbins, a flexible belt on said drums and a plurality of clamps on said belt in spaced relation for clamping the weft ends of the bobbins against the belt, each clamp being so mounted as to move away from the belt as it travels about the drum to release its clamping engagement with the weft ends, said lower drum being so positioned that release occurs at a time after the bobbin is transferred to the shuttle.

11. A thread holder for a weft replenishing loom having a reserve supply of bobbins from which extend weft ends, comprising a pair of drums each freely rotatably mounted in spaced relation and rotatable in a plane substantially at right angles to the axes of the bobbins, a flexible belt on said drums and a plurality of clamps on said belt in spaced relation for clamping the weft ends of the bobbins against the belt, each clamp being so mounted as to move away from the belt as it travels about the drum to release its clamping engagement with the weft ends, said lower drum being so positioned that release occurs at a time after the bobbin is transferred to the shuttle and a stripper plate to remove the yarn from the belt clamps.

GEORGE WM. PARKIN.
